(57) **CLAIM**

The ornamental design for a set of fruit toys, as shown and described.

DESCRIPTION

The file of this Patent contains at least one drawing/photograph executed in color. Copies of this patent with color drawings/photographs will be provided by the office upon request and payment of the necessary fee.

FIG. 1 is a front perspective view of the first toy of the set of fruit toys showing my new design;

FIG. 2 is the back perspective view of the first toy;

FIG. 3 is a front perspective view of the second toy;

FIG. 4 is the back perspective view of the second toy;

FIG. 5 is a front perspective view of the third toy;

FIG. 6 is the back perspective view of the third toy;

FIG. 7 is a front perspective view of the fourth toy;

FIG. 8 is the back perspective view of the fourth toy;

FIG. 9 is a front perspective view of the fifth toy;

FIG. 10 is the back perspective view of the fifth toy;

FIG. 11 is a front perspective view of the sixth toy;

FIG. 12 is the back perspective view of the sixth toy;

FIG. 13 is a front perspective view of the seventh toy;

FIG. 14 is the back perspective view of the seventh toy;

FIG. 15 is a front perspective view of the eighth toy;

FIG. 16 is the back perspective view of the eighth toy;

FIG. 17 is a front perspective view of the ninth toy;

FIG. 18 is the back perspective view of the ninth toy; and,

FIG. 19 is a front perspective view of the set of fruit toys, showing my new design.

The individual fruit toys shown in FIGS. 1-18 are shown separately for the convenience of illustration.
